DEVICE FOR SUPPORTING AND MOVING A
LENS IN THE OPERATION OF BEVELING
THE SAME

Morten Suben, New York, N. Y.

Application December 4, 1948, Serial No. 63,566

7 Claims. (Cl. 51--237)

1

This invention deals with devices in the form of a hand tool for use in supporting and rotating a lens in the operation of beveling peripheral edges of the lens to finish such edges. More particularly, the invention deals with a hand tool or device of the character described, comprising a pair of pivoted jaw and handle members, with means normally tensioning the handle members of the tool to maintain gripper discs of the jaw members in firm and secure engagement with a lens. Still more particularly, the invention deals with a tool of the class described wherein one jaw and handle member of the tool includes means comprising a manually actuated plunger for rotating a lens supported between the jaws, at least a complete revolution, to facilitate grinding or beveling of the peripheral edge of the lens.

The novel features of the invention will be best understood from the following descriptions when taken together with the accompanying drawing, in which certain embodiments of the invention are disclosed, and in which the separate parts are designated by suitable reference characters in each of the views, and in which:

Fig. 1 is a sectional plan view of a tool or device made according to my invention, indicating the method of supporting a lens therein, the section being substantially on the line 1—1 of Fig. 2.

Fig. 2 is a broken section on the irregular line 2—2 of Fig. 1, showing parts of the construction broken away.

Fig. 3 is a section on the line 3—3 of Fig. 1.

Fig. 4 is a section on the line 4—4 of Fig. 1; and

Fig. 5 is an enlarged sectional detailed view similar to Fig. 1, showing only a part of the construction.

In the art of grinding optical and other lenses, it has been customary to provide one or two bevels at peripheral edges of the lens to finish such edges of the lens, or to adapt the lens to different mountings. The common method of procedure in performing operations of the kind under consideration has been for the grinder to hold the lens in his hand with the peripheral edge against a grinding wheel and to rotate the lens so as to move the peripheral edge over the grinding wheel in the operation of beveling the edge. This operation has required considerable skill and care by the operator, particularly in producing a smooth and uniform bevel. Further, this operation has been very tiring, from the standpoint that the hand is required to firmly hold the lens, while the lens is simultaneously rotated in the hand.

2

My improved device or tool has on the surface of the jaw members thereof, a pair of yieldable gripper rings adapted to firmly and fixedly engage a lens arranged therebetween, and further, means is provided on the tool, or at least one jaw and handle member thereof for rotating the lens in the tool. Means is also provided on each jaw for applying thumb pressure on the jaw end of the tool in the operation of grinding either one or two bevels on the peripheral edge of the lens. At this time, it will also be apparent that the manual rotation of the lens is such as to rotate the lens slightly greater than a complete revolution in each series of rotary operations of said lens, so that a substantially uniform and even bevel is provided on the peripheral edge of the lens.

In the accompanying drawing, I have shown one adaptation of my invention, in which the tool comprises two pivotally coupled parts 10 and 11, the part 10 having a pivot-bearing portion 12, fitting and operating in a socket 13 in the part 11, and a pivot pin 14 forms the pivot of said parts. Each part 10 and 11 has a jaw end portion 15 and 16 respectively and a long handle portion 17 and 18. The handle member 18 has a socket 19 for the reception of a heavy coil spring 20, which bears against the handle 17 to normally move the jaw end portions toward each other in gripping and securely holding a lens 21 between grippers 22 and 23. Each gripper 22 and 23 is in the form of a cup or disc 24 and 25, rotatably mounted upon an axis 26 and 27, secured in the jaw ends 15 and 16 respectively. Around the axis 26 and 27, the cup 24—25 has a countersunk recess 28—29 for the reception of a pressure or gripper ring 30—31 respectively. The rings 30—31 will have surfaces conforming substantially to the curved contour of the lens or member to be held thereby, as is clearly indicated in Figs. 1 and 5 of the drawing.

Between the cup or disc 24 and the jaw end 15 of the device is arranged a bearing ring 32, so as to minimize frictional engagement and provide for a relatively free rotation of the disc 24 on the axis 26. The cup or disc 25 has an extension 33, shaped to form a bevelled gear surface 34. In actual practice, the parts 33—34 can comprise a separate member which is secured to the disc 25 in any desired manner. The disc 25, or the extension 33 thereof, also bears against a bearing ring 35, similar to the ring 32, to minimize frictional engagement in rotation of the disc 25 about the axis 27.

As will clearly appear from a consideration of

Fig. 1 of the drawing, the part 10 is actually in the form of a long relatively thin member having the pivot bearing portion 12 projecting from the inner surface thereof, whereas the part 11 is relatively thick. The part 11 is recessed in the irregular fashion clearly seen at 36, in Fig. 1 of the drawing to receive a supplemental part 11', the latter operating as a retaining plate to hold the several devices in the part 11, as later described. The cutout as at 36 is such as to strike centers of certain bores or apertures and is of sufficient depth to meet the center of the axis of a shaft 37, as clearly seen in Fig. 2 of the drawing.

At one end of the shaft 37 is secured a bevelled gear 38 which seats and operates in a cutout or recessed portion 39, in the part 11, as well as the part 11'. To the other end of the shaft 11 is secured a pinion 40. Also arranged between the parts 11—11' is a stub shaft 41, on which is arranged a gear 42 which meshes with the pinion 40. On the shaft 41 is a pinion 43 with which a rack bar 44 is adapted to operate, the bar being secured to and movable with a plunger bar 45. The plunger bar 45 is supported and guided in the parts 11—11' by a pair of pins 46 on which are arranged springs 47. The pins 46 are suitably guided between the parts 11—11' or apertures 48 formed between said parts, one of which is indicated at the right of Fig. 2, whereas the parts have large recesses 49 opening through one surface of said parts for the reception of the springs 47 and other large recesses 50 in the part 11 for reception of adjustable stops 51 arranged on the threaded ends 52 of said pins. By virtue of this construction, the plunger bar 45 can be manually depressed against the action of the springs 47 in rotation of the shaft 37 and rotation of the grippers 22—23 have at least a complete revolution of the lens or other article 21.

A gear ratio will be provided so that the motion of the plunger bar 45 will cause the shaft 37 to rotate at least one revolution, and by slightly reducing the size of the bevelled gear 38 as compared with the gear 38, a greater than one revolution of the workpiece 21 is insured. The purpose of the gearing employed is to minimize the plunger stroke 45 for the performance of the desired function or operation.

At 53 I have shown screws for securing the part 11' to the part 11. It will be apparent that both parts 11—11' are cutout or recessed for the reception of shafts, gears, pinions and so forth, and when the parts 11—11' are assembled, the surfaces of these parts will conform one with respect to the other. In this connection and considering Figs. 3 and 4 of the drawing, it will be apparent that the parts 11—11' have registering curved outer surfaces, as at 54—54' and the outer surface 55 of the part 10 is also curved and this is true of the outer surface 56 of the bar 45. These combined curvatures produce a hand grip portion which will fit comfortably in the hand and facilitate movement of the handle members 17—18 toward each other in separating the grippers 22—23 for insertion and removal of the workpiece 21, as well as the actuation of the plunger bar 45, the latter being intermittently operated in providing a successive series of rotary operations of the workpiece in beveling the peripheral edge 21' thereof, either with a single or double bevel.

Both jaw members have adjacent the pivots 26—27, outwardly curved thumb or fingerpieces 57—58 for applying pressure on the jaw end of

the tool in the grinding of the workpiece while the tool is gripped in the other hand. The two thimble-pieces are employed for supporting the tool in the double-bevelling of the peripheral edge of the workpiece as and when this is required.

In a tool of the character described for use in grinding what is generally referred to as lenses, relatively slight movement is required in the spreading of the grippers to facilitate insertion and removal of lenses of different thicknesses. It will be understood, however, that where the size of the workpiece may be greater, the tool will be constructed accordingly. It will be further understood, that slight frictional movement of the grippers is desirable from the standpoint of providing a more positive control of rotary operation of the workpiece in the operation of grinding the same. However, a minimum amount of pressure is required on the plunger bar 45 to accomplish this result, and after little experience, an operator can become very efficient in the handling of the tool to provide substantially accurate beveling of peripheral edges of workpieces of the kind under consideration. It will, of course, be apparent that my improved tool can be utilized to support any type or kind of workpiece in performing operations thereon, particularly wherein it is desirable to rotate the workpiece in this operation.

Having fully described my invention, what I claim as new and desire to secure by Letters Patent is:

1. A tool for supporting a disc-type workpiece in the operation of shaping peripheral edges thereof, said tool comprising two pivotally coupled parts, each part having a jaw member at one end and a handle member at the opposite end, each jaw member having a rotatable disc, a friction ring supported on the surface of the disc for engaging a workpiece between said members, means on the handle members for normally urging the jaw members into gripping engagement with a workpiece, manually operated means in one of said parts for rotating the discs of the jaw member in rotation of a workpiece supported thereby, said last named means comprising a drive shaft arranged longitudinally in said part and geared to one of said discs, and means including a plunger operated rack mounted in said part for actuating said drive shaft.

2. A tool for supporting a disc-type workpiece in the operation of shaping peripheral edges thereof, said tool comprising two pivotally coupled parts, each part having a jaw member at one end and a handle member at the opposite end, each jaw member having a rotatable disc, a friction ring supported on the surface of the disc for engaging a workpiece between said members, means on the handle members for normally urging the jaw members into gripping engagement with a workpiece, manually operated means in one of said parts for rotating the discs of the jaw member in rotation of a workpiece supported thereby, said last named means comprising a drive shaft arranged longitudinally in said part and geared to one of said discs, means including a plunger operated rack mounted in said part for actuating said drive shaft, and tensional means actuating said rack for rotating the drive shaft in an opposite direction.

3. A tool for supporting a disc-type workpiece in the operation of shaping peripheral edges thereof, said tool comprising two pivotally coupled parts, each part having a jaw member at one end and a handle member at the opposite

end, each jaw member having a rotatable disc, a friction ring supported on the surface of the disc for engaging a workpiece between said members, means on the handle members for normally urging the jaw members into gripping engagement with a workpiece, one of said parts having a drive shaft arranged longitudinally thereof, means gearing one end of the shaft to one of said discs, a plunger actuated rack on said part adjacent the other end of said shaft, and means comprising a plurality of gears arranged in said part for transmitting motion of the rack to said drive shaft in rotating said discs at least a complete revolution.

4. A tool for supporting a disc-type workpiece in the operation of shaping peripheral edges thereof, said tool comprising two pivotally coupled parts, each part having a jaw member at one end and a handle member at the opposite end, each jaw member having a rotatable disc, a friction ring supported on the surface of the disc for engaging a workpiece between said members, means on the handle members for normally urging the jaw members into gripping engagement with a workpiece, one of said parts having a drive shaft arranged longitudinally thereof, means gearing one end of the shaft to one of said discs, a plunger actuated rack on said part adjacent the other end of said shaft, means comprising a plurality of gears arranged in said part for transmitting motion of the rack to said drive shaft in rotating said discs at least a complete revolution, said rack being manually actuated through a bar, and tensional means for moving said bar and rack in one direction.

5. A tool for supporting a disc-type workpiece in the operation of shaping peripheral edges thereof, said tool comprising two pivotally coupled parts, each part having a jaw member at one end and a handle member at the opposite end, each jaw member having a rotatable disc, a friction ring supported on the surface of the disc for engaging a workpiece between said members, means on the handle members for normally urging the jaw members into gripping engagement with a workpiece, one of said parts having a drive shaft arranged longitudinally thereof, means gearing one end of the shaft to one of said discs, a plunger actuated rack on said part adjacent the other end of said shaft, means comprising a plurality of gears arranged in said part for transmitting motion of the rack to said drive shaft in rotating said discs at least a complete revolution, said rack being manually actuated through a bar, tensional means for moving said bar and rack in one direction, and a plate detachable with said part to give access to said shaft and gears.

6. A tool for supporting a disc-type workpiece in the operation of shaping peripheral edges

thereof, said tool comprising two pivotally coupled parts, each part having a jaw member at one end and a handle member at the opposite end, each jaw member having a rotatable disc, a friction ring supported on the surface of the disc for engaging a workpiece between said members, means on the handle members for normally urging the jaw members into gripping engagement with a workpiece, one of said parts having a drive shaft arranged longitudinally thereof, means gearing one end of the shaft to one of said discs, a plunger actuated rack on said part adjacent the other end of said shaft, means comprising a plurality of gears arranged in said part for transmitting motion of the rack to said drive shaft in rotating said discs at least a complete revolution, said rack being manually actuated through a bar, tensional means for moving said bar and rack in one direction, a plate detachable with said part to give access to said shaft and gears, and each jaw member having an outwardly curved fingerpiece portion.

7. A tool of the character described, comprising a pair of pivotally coupled elongated and substantially straight handle members, jaws extending beyond the pivot of said handle members in a straight line, a disc rotatably mounted in each jaw, each disc having a cushioned gripper surface for frictional engagement with a workpiece arranged between said jaws, one handle member and the jaw thereof being thick and having a detachable plate extending longitudinally thereof, a shaft extending longitudinally between the plate and adjacent surface of said handle member and jaw, a gear at one end of the shaft engaging a gear on the disc of said jaw for rotating both discs and the workpiece supported thereby, a gear at the other end of said shaft, a plunger mounted on said handle member at a position substantially 90° to the other thin handle member, means including a rack on said plunger for actuating the last named gear in manually moving said plunger to rotate said shaft in one direction, and tensional means for actuating the plunger to rotate said shaft in the opposite direction.
